UNITED STATES PATENT OFFICE

156,194

DESIGN FOR AN OAR

Carl N. Beetle, Fairhaven, Mass.

Application December 13, 1947, Serial No. 143,130

Term of patent 3½ years

(Cl. D71—1)

To all whom it may concern:

Be it known that I, Carl N. Beetle, a citizen of the United States of America, residing at Fairhaven, county of Bristol, State of Massachusetts, have invented a new, original, and ornamental Design for an Oar, of which the following is a specification, reference being had to the accompanying drawing, forming a part thereof.

Fig. 1 is a perspective view, showing my new design for an oar;

Fig. 2 is an enlarged sectional view taken substantially along line 2—2 of Fig. 1;

Fig. 3 is an enlarged sectional view taken substantially along line 3—3 of Fig. 1;

Fig. 4 is an enlarged sectional view taken substantially along line 4—4 of Fig. 1; and

Fig. 5 is an enlarged sectional view taken substantially along line 5—5 of Fig. 1.

I claim:

The ornamental design for an oar, substantially as shown.

CARL N. BEETLE.
